[57] **CLAIM**

The ornamental design for a nut holding cup for open end wrench, as shown and described.

DESCRIPTION

FIG. 1 is a perspective view of a nut holding cup for open end wrench showing my new design;

FIG. 2 is a reduced top plan view of the nut holding cup for open end wrench;

FIG. 3 is a front elevational view thereof;

FIG. 4 is a left side elevational view thereof;

FIG. 5 is a right side elevational view thereof;

FIG. 6 is a bottom plan view thereof; and,

FIG. 7 is a top plan view thereof.

The broken line showing of an open end wrench in FIG. 7, is for illustrative purposes only and forms no part of the claimed design.
